UNITED STATES PATENT OFFICE.

LAURITZ W. ANDERSEN, OF WATERBURY, CONNECTICUT, ASSIGNOR TO THE PLUME AND ATWOOD MANUFACTURING COMPANY, OF WATERBURY, CONNECTICUT, A CORPORATION OF CONNECTICUT.

TWO-PIECE SOCKET COVER AND HOLDER.

1,125,248.

Specification of Letters Patent. Patented Jan. 19, 1915.

Application filed February 27, 1913. Serial No. 751,120.

To all whom it may concern:

Be it known that I, LAURITZ W. ANDERSEN, a citizen of the United States, residing at Waterbury, in the county of New Haven and State of Connecticut, have invented a new and useful Improvement in Two-Piece Socket Covers and Holders, of which the following is a specification.

This invention relates generally to electric light fixtures and more particularly to a two piece socket holder, the object of my invention being to improve the connection between the cap and body portions of the holder, and provide a connection which is as well adapted for the key type of socket as the keyless.

Heretofore the cap and body portions have been connected sometimes by a slip or spring joint and at other times by means of screws, but in both instances the connection has proved defective particularly when the body portion is slotted to accommodate the key.

With the object of overcoming all of the defects of socket holders now in use I provide a connection embodying a threaded ring carried by the cap portion of the holder and movable thereon for engagement or connection with the upper end of the body portion.

The invention also embodies various other novel features of construction and combination all of which will be fully described hereinafter and pointed out in the claims.

In the drawings forming a part of this specification, Figure 1 is a perspective view of a socket holder constructed in accordance with my invention, this holder being adapted for a socket of the keyless type. Fig. 2 is a similar view of a holder embodying my invention and having the body portion thereof slotted to receive the key of the socket. Fig. 3 is a vertical sectional view of the two piece socket holder. Fig. 4 is a side view of the cap piece, and Fig. 5 is a side view of the connecting ring.

In carrying out my invention I employ a cap piece A, a body piece B, and a connecting ring C. It will of course be understood that the general form of contour or configuration of the device as a whole may be varied or changed as desired. The cap

piece A is formed with the usual top opening A' through which the conductor wires pass and the lower end A² of this cap piece is of such size as to fit snugly within the upper end of the body portion B, said upper end being threaded as shown at B', these threads being engaged by the thread C' of the connecting ring C. The cap piece A is preferably constructed with a reentrant annular groove or corrugation A³, into which the horizontal flange C³ of the connecting ring is seated, thereby effecting a connection between the cap and ring, this connection however providing the free turning of the ring as hereinafter described. The edge of the ring is preferably milled as shown at C² to facilitate the turning operation.

In operation the lower end of the cap is inserted in the upper end of the body portion, the threaded ring overlapping the threaded upper end of said body portion, or in other words the threaded upper end of the body portion is inserted between the lower end of the cap and the threaded ring carried thereby. The cap and ring are then turned so as to screw the parts together the ring working down upon the threaded end of the body portion and this operation is continued until the lower edges of the cap portion engage the body portion at the point B². This contact will serve to arrest the movement of the cap and then by continuing the turning movement of the ring said parts are all tightly bound together, that is, the upper end of the body portion is securely fastened between the lower end of the cap piece and the encircling threaded ring, and inasmuch as the diameter of the depending portion of the cap piece is fixed it is obvious that the upper end of the body portion will be clamped upon the exterior of a definite or fixed circle and this feature is of particular importance in connection with socket holders which are slotted to receive the key as shown in Fig. 2.

A connection such as herein shown and described is quickly and easily made and adds materially to both the strength and appearance of the article as a whole. It will of course be understood that other means may be employed for effecting the union of the cap and ring and other forms

of connection between the ring and body portion other than threads can also be made to accomplish the same results without departing from the broad principle of my invention.

What I claim is:—

1. A combined socket cover and shade holder adapted to envelop a socket, and comprising a shell threaded at its upper end, 19 a cap-piece having its lower portion adapted to fit into the threaded portion of the shell, and a ring carried by said cap portion and having a depending threaded flange adapted to engage the threaded portion of the shell, 15 as set forth.
2. A combined socket cover and holder comprising a shell adapted to envelop a socket, the upper end of said shell being threaded, a cap adapted to receive the upper portion of the socket and having an annular groove adjacent the lower end thereof, said lower end of said cap being of a size adapted to fit within the threaded portion of the shell, and an angled ring having one 25 portion adapted to engage the annular groove in the cap, the other portion of said ring being threaded and adapted to engage

the threaded portion of the shell, as set forth.

3. A combined socket cover and shade holder, comprising a shell adapted to envelop the body of the socket, a cap adapted to receive the upper portion of socket, the lower end of said cap fitting into the upper end of shell, and a ring carried by said 35 cap and adapted to engage the shell and connect said parts together, as set forth.

4. A socket cover and shade holder, comprising a cap portion, a body portion, and a connecting ring, said ring being carried 40 by the cap and turnable thereon for engagement with the body portion, the lower end of cap fitting into upper end of body.

5. A socket cover and shade holder, comprising a body portion, a cap portion having 45 its lower end fitting into the upper end of the body portion, and means carried by the cap and turnable thereon for connecting the cap and body portions.

LAURITZ W. ANDERSEN.
